ELECTRIC SELECTIVE SYSTEM.

1,286,351.

Specification of Letters Patent.

Patented Dec. 3, 1918.

Application filed May 31, 1910, Serial No. 564,120. Renewed February 11, 1918. Serial No. 216,647.

To all whom it may concern:

Be it known that I, HOWARD L. KRUM, a citizen of the United States, and a resident of Chicago, county of Cook, and State of Illinois, have invented certain new and useful Improvements in Electric Selective Systems, of which the following is a full, clear, and exact description.

The invention relates to selective telegraph systems applicable for the operation of printing telegraphs and the like, and seeks to provide an improved method and system by which the signals or characters of a message can be rapidly transmitted from one station and received or recorded with certainty at a distant station, and which is not liable to be affected by the different conditions and disturbing influences to which the telegraph line may be subjected. A further object of the invention is to provide an improved system which can be duplexed or employed to transmit selective signals in opposite directions over the same line circuit. The invention consists in the features of novelty hereinafter set forth, the preferred arrangement of the circuits of the system being set forth in the accompanying drawings, and the invention being more particularly pointed out in the appended claims.

Figure 1 is a diagram of the circuits in one arrangement of the improved system. Fig. 2 is a diagram of circuits as arranged for the duplex transmission of the signals. Fig. 3 is a diagrammatic representation of the transmitted impulses and of the operation of the selecting devices or relays.

In accordance with the present system, the signals or characters are distinguished by different permutations of a definite number of impulses of opposite polarity. Preferably, there are five impulses in each permutation and the arrangement of circuits shown is designed to employ five impulses in each permutation and, as well known, there are thirty-two permutations of positive and negative impulses when there are five impulses in each permutation, so that thirty-two different signals can be transmitted. By employing an additional sixth impulse in each permutation, the number of signals can be increased to sixty-four. For the ordinary operation of a printing telegraph apparatus, thirty-two permutations are sufficient. How-

ever, for greater certainty of operation and in arranging the present system for duplex work, the line is normally closed and in order to obtain the desired thirty-two different combinations or permutations, it is necessary to transmit a starting impulse which is not varied but is always of the same polarity. For example, if the line circuit is normally connected to the negative side of the battery, the starting impulse for each combination or signal will be positive. If the line is normally connected to the positive side of the battery, the starting impulse of each combination will be negative. The remaining five impulses of each signal will form the thirty-two permutations to effect the desired selective operation of the receiving circuits.

The present system has been applied to an improved transmitting and receiving apparatus devised by Charles L. Krum and myself and set forth in a U. S. Letters Patent No. 1,232,045, dated July 3, 1917. One arrangement of the present improved selective system was set forth in the application referred to in order that the invention therein set forth could be clearly understood. The present improvement is, however, applicable to other forms of transmitting and receiving apparatus.

In some respects the present improved arrangement of transmitting and receiving or selecting circuits and relays may be considered an improvement upon an electric telegraph or selective system devised jointly by Charles L. Krum and myself and set forth in U. S. Letters Patent No. 1,199,011, dated September 19, 1916. In certain other respects the present improved system is essentially different, as hereinafter pointed out.

Fig. 1 is a diagram of the circuits and selecting relays and magnets at one station. A set of signal selecting or pole changing switches A are connected to a set of five line branch conductors 1, 2, 3, 4 and 5. These branch conductors are connected respectively to the normally disengaged or front contacts of a set of five transmitting switches b¹, b², b³, b⁴ and b⁵, arranged to be operated by a set of transmitting relays B¹, B², B³, B⁴, and B⁵. In the arrangement shown, the normally engaged or back contacts of the selecting switches or pole changers A

are connected by conductors 6 to one pole (in the present instance the positive pole) of a divided line battery 7. The normally disengaged or front contacts of these switches 5 are connected by conductors 8 to the opposite or negative pole of the line battery. The center of the divided line battery is connected to the ground or a suitable return wire. The selecting switches or pole 10 changers A are operated in different combinations, preferably by means of a set of finger keys, that is to say, only one of these keys C is shown, but it will be understood that there is one key for each signal or permutation 15 to be transmitted and that each key is provided with a series of projections C¹ which are arranged to operate the pole changing switches A and select the permutation that distinguishes the signal or character 20 represented by the key.

When the system is arranged for transmitting, the line circuit extends from the transmitter switch b¹ through the several transmitter switches b², b³, b⁴ and b⁵ in series, each transmitter switch being connected to the normally engaged or back contact of the next switch in the series by a conductor 9. The last transmitter switch b⁵ is connected by a conductor 10 to the back contact of a 25 normally closed unlocking switch b⁶ which is arranged to be shifted to open position by a relay magnet B⁶. This switch is connected by a conductor 11 to one of the poles of a manually shiftable switch D, the other pole 30 or contact of which is connected by a conductor 12 to the ground or to a return wire leading to a distant station. The switch D is connected to one end of the main line wire or conductor 13 which extends therefrom through opposite coils 14 of a polarized line relay D¹, and thence to the distant station.

Each of the transmitting relays is arranged to operate a normally open switch 45 b⁸ which controls the circuit of the next succeeding magnet or relay of the set. The contact of each switch b⁸ is connected to a coil of the next succeeding relay by a conductor 15 and the switches themselves are 50 connected by a common conductor 16 to the normally engaged or back contact of an unlocking switch b⁷ which is operated by the unlocking relay or magnet B⁶. The conductor 16 also leads to the first transmitter 55 magnet B¹ and to a locking magnet E. This locking magnet, as described in the applications for letters patent above referred to, is arranged to lock the selected key in shifted position and prevent the operation of the 60 other keys, until the transmission of the signal corresponding to the depressed key is completed. For this purpose each key carries a spring-held latch e¹, which, when the key is depressed, is forced by a fixed cam plate e² beneath a universal bar e³. The 65

universal bar is operated by the magnet E and the circuit of the latter is closed whenever any key is partly depressed.

The other or normally disengaged contact of the switch b⁷ is connected by a conductor 17 to the coil of the magnet B⁶ and the switch itself is connected by a conductor 18 to a switch a. This switch is operated together with the pole changing switches A by the keys of the transmitter, 70 but, whereas the pole changing switches are variably operated by the keys, each key of the transmitter is arranged to shift the switch a. This switch is normally open and its contact is connected by a conductor 19 to one pole of a local battery 20. The other pole of the battery is grounded or connected to a suitable return wire.

The local battery wire 19 has several branches, all of which are indicated by heavy lines in the diagram. One branch of this battery wire is connected to a normally open switch b⁹ that is operated by the first transmitter relay B¹. The normally disengaged contact of this switch is connected to 90 the conductor 18 which, as stated, leads to the switch a. The transmitter relays, the unlocking relay B⁶ and the magnet E are all connected on one side to the ground or by a suitable return wire to the local battery. 95

In operation, the switch D is shifted to connect the conductor 11 to the main line wire 13 at the transmitting station, and at the receiving station, the corresponding 100 switch will be employed to ground the main line wire or connect it to the divided line battery by a suitable return wire. When any one of the transmitting keys is depressed, one or more of the five impulse selecting or pole changing switches A will be shifted and one or more of the five line branches 1, 2, 3, 4 and 5 will be connected thereby to the negative side of the line battery while the others remain connected to 110 the positive side thereof. At the same time the switch a will also be shifted by the depression of any key to close the operating circuit from the local battery 20. Current will then flow from the local battery by 115 conductor 19, switch a, conductor 18, unlocking switch b⁷ and by conductor 16 to the coils of the locking magnet E and of the first transmitter relay B¹. The magnet E will thus be energized to lock the shifted key 120 in depressed position and prevent the operation of the remaining keys. The operation of the first transmitter relay B¹ shifts its switch b⁸ to connect the second transmitter relay B² to the local battery through the conductor 16, switch b⁸ and conductor 15. The second transmitter relay B² is then energized and in a similar manner operates its switch b⁸ and connects the third transmitter relay B³ to the local battery. The oper- 125 130

ation of this relay connects the fourth transmitter relay to the local battery and it will then connect the fifth transmitter relay B^5 thereto. The operation of the relay B^5 shifts its switch b^8 and connects the magnet B^6 to the local battery from the conductor 18 to the switch b^8 and the conductor 17 leading therefrom to the coil of the magnet B^6 . The operation of this magnet shifts the unlocking switch b^7 and thereby disconnects the conductor 16 from the local battery and opens the local operating circuit through the transmitter relays and through the magnet E, and the parts operated are restored to normal condition.

The transmitter relay magnets and the magnet B^6 are thus successively connected to the local battery and are operated in order, the circuit therethrough being opened at the end of the operation by the magnet B^6 . This effects the successive operation of the transmitter switches b^1 , b^2 , b^3 , b^4 and b^5 to transmit the selected permutation or code signal by successively connecting the line branches 1, 2, 3, 4 and 5 to the line. When the switch b^1 is shifted, current flows from the divided line battery 7, by the conductors 6 or 8 (in accordance as to whether or not the first pole changing switch A has been shifted) to this switch, thence by conductor 1 to the transmitter switch b^1 through the transmitter switches b^2 , b^3 , b^4 and b^5 in order, to the conductor 11, switch D, conductor 13, through the coils 14 of the line relay D^1 at the transmitting station, thence over the line to the line relay at the receiving station, the latter being, as stated, connected by the switch D at the receiving station to the ground or to a suitable return wire leading back to the divided line battery 7. The first impulse of the code signal or permutation is then transmitted to the line and through the line relays D^1 at the transmitting and receiving stations and this first impulse is positive or negative, in accordance as to whether or not the first selecting switch A has been shifted.

The operation of the second transmitter relay B^2 shifts the transmitter switch b^2 , thereby disconnecting the first line branch 1 from the line and connecting the second line branch thereto. The second impulse of the permutation, either positive or negative, in accordance with the position of the second selecting switch A, is then transmitted over the line. Similarly, the operation of each of the other transmitter relays B^3 , B^4 , and B^5 disconnects the preceding line branch and interrupts the sending of the preceding impulse, connects the succeeding line branch and effects the transmission of the succeeding impulse until all five impulses of the permutation have been transmitted. The transmission of the fifth impulse is interrupted by the operation of the magnet B^6

which shifts the switch b^6 and thereby disconnects the conductor 11 from the set of transmitting switches. This relay also shifts the unlocking switch b^7 to break the local circuit through the transmitting relays, but the local operating circuit through the coil of this relay is held locked in closed position by the switch b^7 , since, when the latter is shifted, current flows from the power wire 18 through the switch b^7 and thence by the conductor 17, through the coil of the relay B^6 . The circuit of the magnet B^6 thus remains in closed condition until the selected key is released to restore the switch a to its normal open condition and thereby disconnect the conductor 18 from the local battery 20. The relay B^6 then remains energized as long as the selected key is held depressed and the transmitting relays and the magnet E are cut off from the local power circuit and also from the line and, although the operator may depress other keys of the machine, no effect will be produced thereby until he releases the depressed key to open the circuit through the relay B^6 .

By this arrangement, it is impossible to overlap the signals in transmission. When any key is depressed, it initiates the operation of the transmitting relays, is locked in depressed condition and the remaining keys are locked against operation by the magnet E until the transmission of the selected permutation is completed. The magnet E is then deenergized, so that the lock-out bar e^3 is restored to normal position and the operator may then depress another key. He cannot, however, transmit the succeeding signal until he releases the key first depressed, since, as stated, it is necessary to do this to open the circuit of the magnet B^6 . The switch b^8 of the last transmitter relay B^5 is connected to the conductor 18 and not to the conductor 16, as are the switches b^8 of the other transmitter relays. The switch b^7 of the unlocking magnet or relay B^6 disconnects conductor 16 from the conductor 18 that leads from the battery and, if the switch b^8 were connected to the conductor 16, the magnet B^6 would open and close its own circuit and a buzzer-like action would be produced.

The line conductor 13, as above stated, passes through the coils 14 of the line relays D^1 , both at the transmitting and the receiving stations. The line relay controls the receiving and printing mechanism, so that the message transmitted is printed both at the transmitting and the receiving stations. A branch of the battery wire 19 extends through opposed coils 22 of the line relay D^1 to the ground and these coils are preferably wound upon the same spools as the coils 14. A branch of the battery wire 19 is also connected to a normally closed unlocking switch F, the contact of which is

connected to a branched power wire 23. One of the branches of this conductor is connected to the armature d of the line relay D^1 which is thus connected to one side of the local battery 20 through the unlocking switch F . The circuit through the local coils 22 of the line relay are always closed during the operation of the apparatus. The armature d is normally held in central position between a pair of contacts 24 and the coils 22 balance one another and take the place of the permanent magnet ordinarily employed in a polarized relay. An impulse passing over the line circuit and through the coils 14 will neutralize one of the coils 22 and will strengthen the other so that the armature d will be shifted into engagement with one or the other of a pair of contacts 24 in accordance with the polarity of the line impulse.

The conductor 23, which is connected to the local battery 20 through the normally closed unlocking switch F and the conductor 19, like the battery wire 19, is shown in heavy lines in the diagram and is provided with a number of branches leading to different portions of the selecting apparatus. The armature d of the line relay connects this operating circuit conductor to one or the other of a pair of conductors 25. The flow of current through the conductors 25 is arranged to selectively control a number of pairs of relays G^1 , G^2 , G^3 , G^4 and G^5 . A series of transfer switches h^1 , h^2 , h^3 and h^4 are arranged in pairs and are adapted to be operated by a set of relays H^1 , H^2 , H^3 and H^4 to successively connect the circuits of the selecting relays G^1 , G^2 , G^3 , G^4 and G^5 to the pair of conductors 25 as the impulses of a given permutation are received. The switches h^1 of the first transfer relay H^1 are connected to the pair of main conductors 25. The switches h^2 of the second transfer relay H^2 are connected by a pair of conductors 26 to the front or normally disengaged contacts of the switches h^1 of the first transfer relay. In a similar way, the switches of the third and fourth transfer relays are connected to the front or normally disengaged contacts of the switches of the preceding transfer relay in the set by pairs of conductors 26. A pair of branch conductors 31 and 31' lead from the back or normally engaged contacts of the first pair of transfer switches h^1 to the coils of the first pair of selecting relays G^1 , a normally closed switch g^1 being interposed in each of these branch conductors. The switch g^1 in the branch conductor 31 is operated by one of the pair of selecting relays G^1 and the branch conductor leads to the other relay G^1 and the switch g^1 interposed in the branch conductors 31' is operated by the second relay G^1 of the pair and leads to the coil of the first relay of the pair. The operation of either of the pair of selecting

relays G^1 will cut out the other selecting relay G^1 of the first pair so that it cannot be operated. In a similar manner, the coils of the second pair of selecting relays G^2 are connected to the back contacts of the transfer switches h^2 by a pair of branch conductors 32 and 32' and the third and fourth pairs of selecting relays G^3 and G^4 are connected to the back contacts of the transfer switches h^3 and h^4 respectively by pairs of branch conductors 33 and 33' and 34 and 34'. Each selecting relay is arranged to open a normally closed switch g^1 in the circuit of the other relay of the same pair, so that when any one of the relays is operated, the circuit of the other relay of the same pair is opened by the switch g^1 in its circuit. A fifth pair of branch conductors 35 and 35' are connected to the front contacts of the fourth pair of transfer switches h^4 .

Each of the selecting relays G^1 , G^2 , G^3 and G^4 is arranged to operate a pair of locking switches g^2 and g^3 that are connected to branches of the battery wire 23 that, as stated, lead from the battery 20 through the conductor 19 and the normally closed locking switch F . The contacts of the switches g^2 are connected to the coils of the respective relays so that, when any one of these relays is energized, the circuit to the local battery 20, will be closed through its coil and held in closed condition by the operation of the corresponding locking switch g^2 . The front contacts of switches g^3 of each pair of selecting relays are connected by conductors 36 to the coil of the corresponding transfer switch H^1 , so that when either of the pairs of selecting relays G^1 is operated, the corresponding transfer switch h^1 will also be operated and the circuit of the local battery 20 through its coil will be held to closed condition so long as either one of the relays G^1 remains energized. In a similar manner, the operation of either one of the pair of selecting magnets G^2 will energize the second transfer switch relay H^2 and the operation of either of the pair of magnets G^3 or G^4 will operate the corresponding transfer switch relays H^3 and H^4 .

As stated, each signal or character is represented by a permutation of five impulses of opposite polarity. The first line impulse will energize the line relay D^1 and shift the armature in one or the other direction, so that the circuit from the local battery 20 may be traced therefrom by the conductor 19, normally closed unlocking switch F , battery wire 23 to the line relay armature d and thence by one or the other of the main conductors 25 to one or the other of the switches h^1 of the first transfer switch relay H^1 and thence by one or the other of the branch conductors 31 or 31' through the switches g^1 therein to the coil of one or the other or the first pair of selecting relays 130

G' and then back to the local battery 20 through the ground or by means of a suitable return wire. It will be understood that the selecting relays G¹, G², G³, G⁴ and G⁵ and the set of transfer switch relays H¹, H², H³, and H⁴ are all connected to ground or by a suitable return wire to the local battery 20. If the first line impulse is positive, the selecting relay G¹ interposed in the 10 branch conductor 31' will be energized and if negative, the selecting relay G¹ in the branch conductor 31 will be energized and this branch conductor will be locked in closed condition at this point. That is to 15 say, the operation of either of the pair of selecting relays G¹ will shift the corresponding set of switches g¹, g² and g³. The operation of the switch g¹ will cut out the other selecting relay of the pair and the operation 20 of the switch g² will close the locking circuit from one of the branches of the battery wire 23 through the coil of the selected one of the first pair of relays and it will be held closed independently of the further operation 25 of the line relay D². The operation of the switch g³ of either of the first pair of selecting relays G¹, will close the local battery circuit through the first transfer switch relay H¹ by connecting the battery wire 23 30 to the coil of the relay H¹ through the conductor 36. The first transfer switch relay H¹ will then operate, disconnect the first pair of branch conductors 31 and 31' from the main conductor 25 and connect the second 35 pair of branch conductors 32 and 32' thereto through the medium of the second pair of transfer switches h² and the conductors 26 that are connected to the normally disengaged or front contacts of the switches 40 h¹ of the first transfer switch relay H¹.

The second line impulse of the permutations passing through the coils 14 of the line relay D¹ will shift the armature d thereof in one or the other direction and will close 45 the local operating circuit from the battery wire 23 and armature d to one or the other of the main conductors 25 to one of the switches h¹ of the first transfer relay H¹, thence by one of the conductors 26 to one of 50 the pair of switches h² of the second transfer relay and thence either by one of the branch conductors 32 or the branch conductor 32' to one or the other of the second pair of selecting and locking relays G². The second 55 line impulse of the permutation will thus select one or the other of the branch conductors 32 or 32' and will lock the local operating circuit through one or the other of the second pair of the selecting relays G². The 60 operation of either of these pair of relays will disconnect the second pair of branch conductors 32 and 32' from the main conductors 25 and will connect the third pair of branch conductors 33 and 33' thereto, so that 65 the third impulse of the set will operate

either one of the two magnets G³ and lock the circuit of the selected magnet in closed condition and the fourth impulse of the permutation will select one or the other of the pair of relays G⁴ and lock its circuit in 70 closed condition. The fifth impulse of the permutation will select one or the other of the branch conductors 35 or 35' and operate one of the pair of magnets G⁵ interposed therein. 75

In the system set forth in the Patent No. 1,199,011, above referred to, there were ten relays in the transmitting set, the first being arranged to connect the first line branch to the line, the second to disconnect it therefrom, the third connecting the second line branch to the line, the fourth disconnecting the second branch, and so on, so that the permutations of any given signal were transmitted with appreciable pauses or interruptions of the main line circuit. In that system, the transfer switches at the receiver which successively connected the pairs of branch circuits and of locking and selecting relays therein to the main conductors controlled by the line battery, operated at the pauses or interruptions of the main line circuit between the separate impulses of the permutation. The second transmitting relay B² in the system here shown, not only disconnects the first line battery 1, but connects the second line battery 2 thereto and the third relay B³ disconnects the second line branch 2 and connects the third line branch 3 thereto and so on, so that the impulses of any given permutation follow one another with great rapidity and with practically no, or only very slight, interruptions in the line circuit. At least, the effect of the inductive capacity of the line and the magnetic lag of the line relays is such that the slight interruptions in the line circuit between the successive impulses does not affect the line relay and its armature is not moved when the transmission of any given permutation is commenced unless the current in the line circuit is reversed, as when a negative impulse follows a positive, or vice versa. It follows from this that two succeeding impulses of the same polarity at the receiver 110 form in effect one long impulse of double length and three impulses, a long impulse of three times the length of an ordinary impulse. It follows that the selecting relays must be variably responsive to different 115 lengths of impulses and be independent of any interruptions in the line circuit between the impulses of like polarity in any given signal. 120

The transfer switch relays in the present 125 system, instead of acting at the pauses between the impulses of the permutation as in the prior system referred to, operate as above described, as soon as either one of the corresponding pair of selecting magnets is 130

energized and the speed of operation of the selecting and transfer switch relay magnet is tuned to correspond with the speed of operation of the transmitting relays.

- 5 The first impulse of a permutation is sent to the line as soon as the first transmitting relay B^1 is energized. At the same time, the circuit of the second transmitting relay B^2 is connected to the local battery and the length 10 of the first impulse depends upon the time required for the second relay B^2 to operate. In the same way, the length of the succeeding impulses in the permutations depend upon the length of time it requires the 15 succeeding transmitting relays to operate. These transmitting relays are relatively slow acting, so that heavy, strong impulses may be impressed upon the line circuit. The selecting relays G^1 , G^2 , G^3 , G^4 and G^5 of the 20 receiver are preferably very sensitive, quick-acting magnets so that they will quickly respond to the operation of the line relay D^1 , while the transfer switch relays H^1 , H^2 , H^3 and H^4 which are operated from the local 25 battery through the medium of the selecting relays, may be relatively slow-acting. The timing of the transfer switch and selecting 30 relays is such that, the time required for one of the first pair of selecting relays G^1 and the first transmitting switch relay H^1 to operate is the same as required by the second transmitting relay B^2 to operate. The time required to operate one of the second pair of 35 selecting relays G^2 and the second switch relay H^2 is the same as is required by the transmitting relay B^3 . In a similar manner, the time of operation of one of the third set of selecting relays G^3 and the transmitting switch relay H^3 and of one of the selecting 40 relays G^4 and the transfer switch relay H^4 correspond respectively to the time of operation of the transmitting relays B^4 and B^5 . By reason of this arrangement, it is not necessary to interrupt the line circuit between 45 the impulses of like polarity in any given permutation. For example, if the first two impulses of any permutation are of the same polarity to give in effect one impulse of double length, it will first, as described, operate one of the pair of selecting relays G^1 and the transfer relay H^1 and then properly operate one of the selecting relays G^2 and the transfer switch relay H^2 . If this 50 double impulse is positive, the branch conductors 31' and 32' will be selected and if negative, the branch conductors 31 and 32 will be selected. If the first three impulses of the permutation are of the same polarity thereby forming in effect at the receiver one 55 long impulse of three times the length of an ordinary impulse, and the third pair of selecting relays G^3 will be operated and the third transfer relay H^3 and one or the other of the branch conductors 33 or 33' will be 60 selected.

Impulses of like polarity in any given permutation or signal can thus follow one another without any appreciable interruption of the line circuit. At least, there need not be sufficient interruption in the line circuit 70 to cause the armature of the line relay to drop back from one of the contacts 24, since the set of selecting relays will variably respond to the different lengths of impulses formed by crowding together succeeding impulses of like polarity in any permutation. After the transmission of the permutation is once initiated, the only changes occurring in the line circuit are reversals of polarity. The transmission of the succeeding impulses 80 of any permutation may therefore be effected rapidly. Moreover, the proper selective operation of the system is not interfered with by the inductive capacity of the line or the magnetic lag of the line relays, 85 since it is not necessary that there should be distinct pauses between the impulses and since reversals on the line will quickly overcome the lag due to either of these causes. Moreover the system is not liable to be affected by different weather conditions or by 90 other disturbing influences.

It is not necessary that the synchronous operation or tuning of the transmitting and receiving relays be absolutely accurate. 95 Fig. 3 indicates diagrammatically the operation of the different relays when a permutation comprising two positive impulses, two negative impulses and a fifth positive impulse is transmitted. The first impulse 100 begins at the operation of the first transmitting relay B^1 and its length is determined by the period of operation of the second transmitting relay B^2 . In a similar manner the lengths of the succeeding impulses are 105 determined by the period of operation of the magnets B^3 , B^4 , B^5 and B^6 . There is little or no appreciable pause between the impulses and in ordinary operation there is not a sufficient interruption between successive impulses of like polarity to affect the line relays. It is obvious from these diagrams that it is only necessary that one of the pair of magnets G^1 operate at some portion of the time that the first impulse of any 110 permutation is passing over the line circuit and that the succeeding selecting relays operate at some portion of the time, during which the corresponding impulses are passing over the line circuit. When an impulse of 115 negative polarity follows an impulse of positive polarity or vice versa in a permutation or signal, it is not necessary that the reversal of the line circuit shall occur in absolute synchronism of the operation of the corresponding transfer relay since, when one of the pair of selecting relays is operated it cuts out the other relay of the same pair by means of its switch g^1 . For example, if the second impulse of a permutation is positive 120

and the third negative, the positive impulse will operate the selecting relay G^2 in the branch conductor 32' and will cut out the relay G^2 in the branch conductor 32 which responds to negative impulses, then, if the line reversal occurs before the transfer switch H^2 has completed its operation, it cannot affect the negatively responsive, selecting relay G^2 and it is only necessary that this second impulse shall be prolonged sufficiently to select the negatively responsive relay G^3 of the third pair and thereby connect the branch conductor 33 to the local battery.

This arrangement not only permits the impulses of any given permutation to follow one another very rapidly and thereby increase the speed of transmission of messages, but also avoids the difficulty heretofore encountered in electric selective systems, due to the lag of the line circuit which varies with the length and capacity of the line, with the weather conditions and with the adjusting of the line relays. As explained above, the synchrony in the operation of the transmitter and receiver need not be absolutely perfect. Moreover, inasmuch as the transmitting and selecting relays are restored to normal position at the end of any complete permutation or code signal, the transmitter and receiver start in perfect synchrony at the beginning of each signal.

The variable operation of the magnets G^1 , G^2 , G^3 , G^4 and G^5 may be employed to make the signal in any suitable manner. For example, they could be employed to operate a series of switches of a fan circuit in manner set forth in the Patent No. 1,199,011, above referred to, or could be employed to control the operation of a set of mechanical selecting devices, as set forth in the other patent referred to No. 1,232,045.

At the complete operation of any signal the normally closed unlocking switch F is opened, to restore the selecting circuits of the receiver to normal condition in readiness to receive the next permutation or signal. This switch may be opened in any suitable manner. In the arrangement shown, it is controlled by a magnet F^1 , the circuit of which is arranged to be closed from a battery wire 19 through a pair of normally open switches g^4 , and a conductor 37 leading to the coil of the magnet F^1 . The switches g^4 are operated by the last pair of selecting magnets or relays G^5 , so that when either of these magnets is operated, the circuit of the unlocking magnet F^1 will be completed and the switch F operated to disconnect all portions of the receiver from the local battery and thereby permit the restoration of all parts to normal condition.

In the arrangement shown in Fig. 1, the line circuit is normally open. The arrangement shown in Fig. 2 is designed more par-

ticularly for duplex operation and the line circuit is normally closed. The arrangement of the transmitter is similar to that shown in Fig. 1, except that an additional starting relay B is added to the set of transmitting relays. This relay controls the switch b^9 which connects the battery wire 19 to the conductor 18. It also controls a switch b which is connected by a conductor 37 to a normally engaged or back contact of the transmitter switch b^1 which is operated by the relay B^1 . The front and back contacts of the switch b are connected by extensions 6' and 8' of the conductors 6 and 8 to the opposite sides of the divided line battery 7, the arrangement being such that the negative side of the divided battery is normally connected to the line through the conductor 6', switch b , conductor 37, the set of transmitter switches b^1 , b^2 , b^3 , b^4 and b^5 , connected by the wires 9, the conductor 10, switch b^6 and conductor 11'. The conductor 11' is connected by branch conductors 38 to the separate coils of a differential polarized relay K and thence through one coil to a line conductor 39, and through the opposite coil to an artificial line comprising an adjustable resistance 40 and a condenser 41. The adjustable resistance and condenser forming the artificial line are, as usual, grounded.

The starting relay B also controls a switch b^8 which connects the conductor 16 to the coil of the succeeding relay B^1 by a conductor 15. The set of transmitting relays, like that shown in Fig. 1, operate in order to successively connect the line branches 1, 2, 3, 4 and 5 to the line. As the line is normally closed, a starting or controlling impulse must be transmitted over the line to initiate the operation of the selecting receiver. This is effected by the relay B which disconnects the conductor 6' from the line and connects the conductor 8' thereto, so that the first impulse of any signal is always positive and cannot be varied to aid in the selection of the different characters. Each signal must therefore be made up of six impulses, the first of which is merely a starting impulse and the others are varied to obtain the thirty-two permutations or signals. At the end of the transmission of each signal, the line is again connected to the negative pole of the battery by the switch b^9 . The last transmitter switch b^6 has a normally disengaged contact connected to the conductor 6' so that negative current is applied to the line when this switch is operated.

A branch 42 of the conductor 11' extends through a polarized relay K^1 to the ground or to a suitable return wire. This relay controls a home recorder at the transmitting station and the relay will of course respond to such transmitted impulses, but the duplex relay K will only respond to impulses received from a distant station. Pref- 130

erably the conductor 11' extends through two polarized relays in succession, one of which controls the home recorder and the other of which controls a circuit extending through

5 the coils of the differential relay to the line conductor and to the grounded artificial line.

The recorders for transmitted and received signals controlled respectively by the relays K¹ and K are alike. The armatures k of

10 these relays are connected to the battery wire 19 through normally closed unlocking switches L and a branched conductor 43. The two contacts 44 and 45 of each armature k are respectively connected by two conductors

15 46 and 47 to two switches m³ and m⁴ which are arranged to be operated by a magnet M⁴. The normally closed or back contacts of these switches are connected to a pair of conductors 48 and 49 which lead, re-

20 spectively, to the switches m and n of a pair of starting relays M and N. The conductor 49 also extends to the coil of the magnet N. The relays M, N and M⁴ form part of a set or series of magnets, the other magnets or

25 relays of the series being designated by the letters M¹, M², M³ and N¹, N², N³ and N⁴. These magnets are all alternately arranged in a series, as shown, and each magnet of the series is arranged to close the circuit of

30 the succeeding magnet in the set, so that when the operation of the set is once initiated, they will operate in order.

The normally disengaged contact of the switch is connected to the battery through the

35 normally closed unlocking switch L by means of the branch conductor 43. As the line is normally closed, the armature k of the line relay normally engages the contact 44. The first impulse of all signals is of the same

40 polarity—positive in the arrangement set forth—and serves to shift the armature into engagement with the contact 45. This closes the circuit of the local battery through the conductor 19, unlocking switch L, conductor

45 43, armature k, contact 45, conductor 47, switch m⁴, conductor 49, through the starting relay N. It will be understood that all the relays are connected either to ground or by a suitable return wire to the local battery.

50 The switch n of the starting relay N then locks the circuit, through the coil of the relay N, in closed condition by connecting the battery wire 43 thereto. It also locks the conductor 49 into connection with the conductor 43. The conductor 49 is connected to

55 a series of switches n⁵ which are arranged to be operated one by each of the set of relays N, M, N', M', etc. The normally disengaged contact of the switch n⁵ of each relay is connected to the coil of the next relay of the

60 set by a conductor 50. Thus, when the starting relay N is operated, the succeeding relays will be successively connected to the battery through the conductor 19, unlocking switch L, conductor

49 and the switches n⁵ which operate in order to connect the set of relays successively to the local battery through the medium of the conductors 50.

In addition to the successively operating 70 relays, each receiver has a set of selecting magnets or relays P¹, P², P³, P⁴, P⁵ and P⁶.

These magnets are all connected on one side to the local battery through the ground or a suitable return wire. On the opposite side 75

magnets P¹, P², P³ and P⁴ are connected, respectively, by a set of conductors 51, 52, 53 and 54 to a series of normally closed switches n¹, n², n³ and n⁴ which are operated 80

respectively by the relays N¹, N², N³ and N⁴. The selecting relays P⁵ and P⁶ are connected

85 by a pair of conductors 55 and 56 to the normally disengaged contacts of the switches m³ and m⁴. The normally engaging contacts of the closed switches n¹, n², n³ and n⁴ are connected by conductors 57 to the contacts of a set of normally open switches m and m'. These switches are connected to branches of the conductor 48 and are ar-

90 ranged to be operated in order by the magnets M, M¹, M² and M³ when the set of receiving relays are operated in order. In

95 this way local branch conductors which include the selecting magnets or relays P¹, P², P³ and P⁴ are successively connected one at

99 a time, as any signal is received, by the switches m, m¹, n¹, n², n³ and n⁴ to the conductor 48. This conductor, however, is only connected to the local battery through the

100 contact 44 by means of the switch m³, conductor 46, contact 44, relay armature k, conductor 43 and locking switch L and conductor 19. The armature k only engages the

105 contact 44 when the negative impulse is received. The set of relays N, M, etc., operate in order whenever any signal is received. They are also timed to operate in substantial synchronism with the speed of transmission or lengths of the impulses of any signal. In this way, the circuit of the se-

lecting relay P¹ will be connected to the contact 44 of the line relay when the first impulse is received, and will be operated if the first impulse is negative, but will remain un-

110 affected if the first impulse is positive. In a similar manner the selecting relays P², P³ and P⁴ are successively connected to the contact 44 of the line relay as the second, third and fourth impulses are received and will be

115 variably operated in accordance with the polarity of such impulses. When the last impulse of any permutation is received, the relay M⁴ is operated and connects the circuit of the two selecting relays P⁵ and P⁶ to the

120 contacts 44 and 45 of the line relay through the pairs of conductors 46, 47 and 55, 56, and switches m³ and m⁴ so that one or the other of these magnets will be operated in

125 accordance with the polarity of the last impulse of the signal.

The operation of any of the selecting magnets P^1 , P^2 , P^3 and P^4 will lock the local battery in closed condition through its own coil by means of a normally open locking switch P^7 , which serves to connect the local battery to the coil of the corresponding selecting magnet from the wire 19, unlocking switch L and branch conductor 43. Thus, when any one of the selecting relays is operated, its circuit will remain in closed condition until the unlocking switch L is opened. The variable operation of the set of selecting magnets can be arranged to make or record a signal in any suitable manner, for example, as set forth in the patents referred to. At the completion of any signal, the operation of one or the other of the selecting magnets P^5 or P^6 will operate one of a pair of switches P^8 and thereby close the circuit through a coil of the magnet L^1 from the battery wire 19, switch P^8 and conductor 58. The magnet L^1 serves to open the unlocking switch L and restore the recording relays to normal condition.

Here, as in the arrangement shown in Fig. 1, it is not necessary that the transmitter and receiver operate in exact synchronism. To assist in the tuning or timing of the two sets of transmitting and receiving relays, they are preferably connected to the local battery through return conductors 59 and 60, having adjustable resistances 61 interposed therein, so that the speed of operation of the two sets may be controlled, as desired.

The successively acting receiving magnets, shown in Fig. 2, could of course be arranged to operate upon the open circuit with five impulses in each permutation, as in the arrangement or system shown in Fig. 1. In such case, however, the magnets B , M and N could be omitted, but the system could not be readily operated for the duplex transmission of messages. Similarly, by adding the starting magnets or relays to the arrangement shown in Fig. 1, similar to the magnets B , M , and N , that arrangement could be employed with a normally closed circuit and a differential line relay or the duplex transmission of signals.

It is obvious that numerous changes can be made in the details and arrangements of circuits set forth without departure from the broad scope of the invention, as defined in the claims.

I claim as my invention:

1. In printing telegraphy, the method of selective signaling which consists in operating a transmitter solely under local control to impart to a line character signals of uniform length and each comprising the same number of positive or negative impulses in quick succession and without perceptible spacing intervals between the impulses, initiating the operation of a selecting receiver

switch mechanism in response to transmitted impulses at the beginning of each signal, timing the operation of the switch mechanism in synchronism with the transmitted impulses of each signal independently of the line circuit and restoring the same to a condition of rest at the completion of each signal.

2. In printing telegraphy, the method of selective signaling which consists in operating a transmitter solely under local control to impart to a line character signals of uniform length and each comprising a different permutation of a definite number of impulses of opposite polarity, locally timing the operation of a receiver switch mechanism to associate the selecting devices of the receiver successively with the line in synchronism with the transmitted impulses of the character signals to thereby variably operate the same in different combinations, and, at the end of each signal, arresting the operation of said switch mechanism and again starting the same in response to the first transmitted impulse of the succeeding signal.

3. In printing telegraphy, the method of selective signaling which consists in normally maintaining current on a line, imparting to the line character signals each comprising a different permutation of five impulses of opposite polarity preceded by a line current reversal or starting pulse, controlling at each character selection, the initial operation of a selecting receiver in response to said transmitted starting impulses, and thereafter, under local control and at spaced intervals corresponding with the midportions of the permutation impulses, successively bringing the selecting devices of the receiver into operative relation with the line to thereby effect the character selections.

4. In printing telegraphy, the method of selective signaling which consists in normally maintaining current on a line, operating a transmitter solely under local control to impart to the line character signals of uniform length and each comprising a different permutation of two different line conditions extending through a definite number of time intervals, initiating the operation of a selecting receiver in response to the first change in line condition of each signal and thereafter, under local control and at spaced intervals corresponding with the mid-portions of said time intervals, successively bringing the selective devices of the receiver successively into operative relation with the line to variably operate the same in accordance with the two different line conditions.

5. In printing telegraphy, the method of controlling a selecting receiver which consists in operating a transmitter solely under local control to impart to a line character

- signals of uniform length and each comprising a different permutation of positive and negative impulses in quick succession and without perceptible spacing intervals, initiating the operation of the receiver switch mechanism at the beginning of character signals and in response to impulses imparted to the line by said transmitter, locally timing the operation of said switch mechanism
- 10 to associate the receiver selecting devices with the line successively and at spaced intervals corresponding with portions only of the transmitted impulses and, at regular intervals between character signals, arresting the operation of said switch mechanism.
- 15 6. In telegraphy, the method of selective signaling which consists in transmitting permutations of a definite number of impulses of opposite polarity and of uniform length over a normally closed line circuit, initiating the operation of a series of selecting devices at the receiver by the first impulse of each permutation or signal, electro-magnetically maintaining the operation of said selecting devices in synchronism independently of the transmitted impulses, and restoring the selecting devices to normal at the completion of each signal.
- 20 7. In selective systems for printing telegraphs, the combination with a normally closed line, a transmitter having a normal condition of rest, and operative under local control for imparting to the line character signals of equal length, means for initiating the operation of said transmitter, the latter having means independent of said starting means for restoring the line to normal at the end of each signal, a receiver having a set of selecting magnets, transfer
- 25 switch mechanism for associating said selective magnets with the line in predetermined order, means responsive to the first impulse of each signal for initiating the operation of said switch mechanism, and locally timed means for controlling such operation in synchronism with said transmitter and for restoring said switch mechanism to a condition of rest at the end of each signal.
- 30 8. A selective system for printing telegraphs comprising a line, transmitter switch mechanism operating solely under local control to impart to the line character signals of equal length and each comprising the same number of positive or negative impulses in quick succession and without spacing intervals between the impulses, a receiver having a set of selecting magnets, transfer switch mechanism for successively
- 35 associating said magnets with the line to thereby variably operate the same in combinations according to the polarity of the signal impulses, means, locally timed in operation, for maintaining said switch mechanism in synchronism with the transmitted

impulses of the character signals, means for arresting the operation of said switch mechanism at regular intervals and at the end of character signals, and means responsive to impulses imparted to the line by said transmitter for again initiating the operation of said switch mechanism.

9. A selective printing telegraph system comprising a line, transmitter switch mechanism for imparting thereto character signals of equal length and each comprising a different permutation of impulses of opposite polarity, a receiver having a set of selecting devices, transfer switch mechanism initiated in operation by the first transmitted impulse of each signal but otherwise locally controlled, for successively associating said selecting devices with the line to thereby variably operate the same in different combinations and in accordance with the polarity of the transmitted impulses, means for maintaining said selecting devices in operated condition, and means for restoring the same to normal at the end of each signal.

10. In selective systems for printing telegraphs and the like, in which the signals are represented by permutations of a definite number of impulses of opposite polarity, the combination with a normally closed line circuit, of a transmitter for imparting the permutations of impulses or signals each preceded by a starting impulse to the line, and a selecting receiver having means controlled by the transmission of each starting impulse for initiating the operation thereof, electromagnetic devices for effecting the successive operations of the receiver in synchronism with the transmitted impulses but independently of the line circuit, and means for arresting the operation of the receiver at the completion of each permutation or signal.

11. In selective systems for printing telegraphs and the like in which the signals are represented by permutations of a definite number of impulses of opposite polarity, the combination of a transmitter for imparting the permutations of impulses or signals to the line at a definite rate, a selecting receiver comprising a set of magnets arranged to operate in order and having periods of operation corresponding to the lengths of the impulses of each signal, whereby successive impulses of like polarity in any signal can follow one another on the line circuit without intermediate breaks.

12. In selective systems for printing telegraphs and the like in which the signals are represented by permutations of a definite number of impulses of opposite polarity, the combination of a transmitter for imparting the permutations of impulses or signals to the line at a definite rate and without perceptible breaks or pauses be-

tween impulses, a synchronously operating receiver arranged to respond variably both to the impulses of opposite polarity and to impulses of like polarity but of different 5 lengths and electro-magnetic means responsive to the first impulses of the signals for controlling the initial operation of said receiver at each character selection.

13. In selective systems for printing telegraphs and the like in which the signals are represented by permutations of a definite number of impulses of opposite polarity, the combination of a transmitter for imparting the permutations of impulses or signals to 10 the line at a definite rate, a series of selecting relays, and a series of intermediate spacing or transfer relays, said selecting and intermediate relays being arranged to operate in order and in synchronism with said transmitter independently of spacing intervals between the impulses.

14. In selective systems for printing telegraphs and the like in which the signals are represented by permutations of a definite number of impulses of opposite polarity, the combination of a transmitter for imparting the permutations of impulses or signals to the line at a definite rate, a series of selecting relays arranged in pairs, an operating circuit 25 for said relays, and means controlled by the operation of either relay of a pair for immediately connecting the succeeding pair of relays to said operating circuit.

15. In selective systems for printing telegraphs and the like in which the signals are represented by permutations of a definite number of impulses of opposite polarity, the combination of a transmitter for imparting the permutations of impulses or signals to 30 the line at a definite rate, a series of selecting relays arranged in pairs, an operating circuit for said relays, a line relay controlling said operating circuit, a set of transfer switch relays, means controlled by the operation of either selecting relay of a pair for immediately energizing the corresponding transfer switch relay to connect the succeeding pair of selecting relays to said operating circuit, said relays being timed to 35 operate in synchronism with said transmitter.

16. In selective systems for printing telegraphs and the like in which the signals are represented by permutations of a definite number of impulses of opposite polarity, the combination of a transmitter for imparting the permutations of impulses or signals to the line at a definite rate, a receiver comprising a set of selecting magnets arranged 40 to be variably energized by the impulses of each permutation or signal, a line relay controlling the circuits of said selecting magnets, and electromagnetic means initiated in operation at intervals by transmitted impulses but otherwise locally timed to op-

erate in synchronism with said transmitter for successively connecting said selecting magnets to said line relay.

17. In selective systems for printing telegraphs and the like in which the signals are represented by permutations of a definite number of impulses of opposite polarity, the combination of a transmitter for imparting the permutations of impulses or signals to the line at a definite rate, a receiver comprising a set of selecting magnets arranged to be variably energized by the impulses of each permutation or signal, a line relay controlling the circuit of said selecting magnets and a set of relays, the circuit of each of which is controlled by a preceding magnet of the set, means controlled by the first impulse of any signal for initiating the operation of said set of relays, said relays being tuned to operate in synchronism with said transmitter, and means controlled thereby for successively connecting said selecting magnets to said line relay.

18. In selective systems for printing telegraphs in which the signals are represented by different permutations of a definite number of impulses of opposite polarity, the combination of a transmitter for imparting the permutations of impulses or signals to the line at a definite rate, means for selecting the signal impulses and for initiating the operation of said transmitter, said transmitter having means independent of said impulse selecting and starting means for restoring the line to normal at the end of each signal, locking means for compelling the complete operation of said transmitter after its operation is once initiated, a receiver adapted to operate under local control in synchronism with said transmitter, means controlled by the first impulse of any permutation or signal for initiating the operation of said receiver, and means for restoring the latter to a condition of rest at the completion of each signal.

19. In electric selective systems in which the signals are represented by permutations of a definite number of impulses of opposite polarity, the combination of a normally closed line circuit, a transmitter at each station for imparting the permutations of code impulses and additional starting impulses to the line circuit, a duplex relay at each station, and a selecting receiver controlled by each duplex relay in response to the permutation and starting impulses received from a distant station.

20. In electric selective systems in which the signals are represented by permutations of a definite number of impulses of opposite polarity, the combination of a normally closed line circuit, a transmitter comprising a set of relays arranged to operate in order to impart the code permutations or signals and additional starting impulses with each

signal to the line, a duplex relay at each station, and a set of synchronously acting selecting relays controlled by said duplex relay and responsive to signals from a distant station.

21. In selective systems for printing telegraphs and the like in which the signals are represented by permutations of a definite number of impulses of opposite polarity, 10 the combination of a transmitter for imparting permutations or signals to the line at a definite rate, a selective receiver arranged to operate in synchronism with said transmitter, means controlled by the transmitter impulses for initiating the operation of said receiver and restoring the same to normal at the beginning and completion respectively of each signal, and means for adjusting the time of operation of said transmitter and receiver to effect the proper synchronous operation.

22. In selective systems for printing telegraphs and the like in which the signals are represented by permutations of a definite 25 number of impulses of opposite polarity, the combination of a transmitter comprising a set of relays arranged to automatically operate in order, a receiver comprising a set of relays arranged to automatically operate in 30 order and in synchronism with the operation of said transmitter relays and means for varying the speed of operation or for tuning the said sets of transmitting and receiving relays to effect proper synchronism.

35 23. A selective system for printing telegraphs comprising a line, a transmitter operating solely under local control to impart to the line character signals, each comprising a different permutation of two different line 40 conditions extending through a definite number of time intervals without perceptible spaces between the intervals, a receiver having a set of selecting magnets, transfer switch mechanism locally timed in operation during each character selection for bringing said selecting magnets into operative relation with the line successively and at spaced intervals corresponding with the mid-portions of said time intervals, 45 means for arresting the operation of said switch mechanism at the end of each character signal, and means responsive to first change in line condition of each signal for initiating the operation of said switch 50 mechanism.

24. A selective system for printing telegraphs, a normally closed line, a transmitter for imparting to the line starting impulses and character signals comprising different permutations of a definite number of 60 successive positive and negative impulses without perceptible spacing intervals between the impulses, a line relay, a receiver having a set of selecting magnets, transfer switch mechanism, locally timed in opera- 65

tion for bringing said selecting magnets into operative relation with said line relay successively and at spaced intervals corresponding to the mid-portions of the permutation impulses, means for restoring said switch 70 mechanism to a condition of rest at regular intervals and at the end of character signals, and means responsive to said starting impulses for again initiating the operation thereof.

75 25. A selective system for printing telegraphs comprising a line, transmitter means adapted to maintain current on said line between character signals and operating solely under local control to impart to the line 80 starting line conditions and character signals of equal length and comprising permutations of two different line conditions without perceptible spacing intervals between the impulses, a line relay, a receiver 85 having a set of selecting devices arranged to be set in different combinations, and means initiated in operation at the beginning of each signal by said starting line conditions but otherwise locally timed in operation, for 90 bringing said selecting devices successively into operative relation with said line relay at spaced intervals corresponding with the mid-portions of the signal impulses, and means for arresting the operation of said 95 locally-timed means at the completion of each signal.

26. In a selecting system for printing telegraphs, the combination with a normally closed line, of a transmitter having a normal condition of rest and being operative to impart starting impulses and character signals to the line, a starting switch for initiating the operation of said transmitter, the latter having means independent of said starting 100 switch for restoring the line to normal condition at the end of each signal, a receiver having a set of selecting devices adapted to operate in different combinations to effect the character selections, transfer switch 105 mechanism, locally timed in operation, for bringing said selecting devices successively into operative relation with the line, means responsive to said starting impulses for initiating the operation of said switch mechanism at the beginning of each signal, and means for restoring the same to a condition 110 of rest at the end of each signal.

115 27. In selective systems for printing telegraphs, the combination of a transmitter for imparting to the line character signals, each comprising a different permutation of two different line conditions extending over a definite number of time intervals, a receiver having a set of selective devices 120 adapted to be operated in different combinations to effect the character selections, and electromagnetic means, responsive to first 125 change in line condition of each signal but otherwise locally timed in operation, for 130

bringing said selective devices successively into operative relation with the line.

28. In selecting systems for printing telegraphs, a receiver having a set of selecting devices variably operated in different combinations, a set of relays locally timed in operation, for bringing said selective devices successively into operative relation with the line, line controlled means for initiating the 5 operation of said set of relays at the beginnings of definite cycles of operation, and means for arresting the operation of said set of relays at the ends of such cycles.

29. In selecting systems for printing telegraphs, a line, a receiver having a set of selecting devices arranged to operate in different combinations to effect the character selections, and a set of relays arranged to operate in invariable predetermined order to 10 successively bring said selecting devices into operative relation with said line during each character selection.

30. In selecting systems for printing telegraphs, a line relay, a set of selecting magnets operating in different combinations to effect the character selections, and a set of transfer relays, said magnets and relays being arranged in separate local circuits and the latter being arranged to operate in pre- 15 determined order to bring said selecting magnets successively into operative relation with said line relay.

31. In selecting systems for printing telegraphs, the combination with a line, of a transmitter for imparting to the line character signals of equal length and comprising different permutations of two different line conditions, a receiver having a set of selecting magnets adapted to operate in different combinations to effect the character 20 selections, transfer switch mechanism, initiated in operation by starting impulses transmitted over said line but otherwise locally timed in synchronism with said transmitter, for bringing said selecting devices successively into operative relation with the line during the character signals, a locking magnet and connections for maintaining said selecting magnets in operated condition, and means for operating said locking magnet and releasing said selecting magnets at the completion of each signal.

32. In a selective system for printing telegraphs, the combination with a line, transmitter and receiver switch mechanisms locally timed in operation during each character selection and having normal conditions of rest, a starting magnet having a local current independent of the line circuit for 25 initiating the operation of said transmitter switch mechanism, a starting magnet controlled by impulses accompanying the transmission of character signals over said line for initiating the operation of said receiver switch mechanism at the beginning of each

character signal, a set of impulse selecting switches for determining the character signals imparted to said line by said transmitter, and a corresponding set of selecting devices successively brought into operative 70 relation with the line by said receiver switch mechanism and thereby variably operated in different combinations to effect the character selections.

33. In a selective system for printing telegraphs in which the character signals are distinguished by permutations of impulses without spacing intervals between the impulses, the combination with a line, transmitters at each of two connected stations 75 normally maintaining current on the line and adapted to impart the character signals thereto, each preceded by a starting signal, each of said transmitters having means locally controlled independently of the line 80 for initiating the operation, and means, independent of said starting means, for restoring the line to normal at the end of each signal, and selecting receivers at each station normally at rest and locally timed in operation, said receivers each having starting means and sets of selecting devices responsive respectively to the starting and character signals imparted to the line by the distant transmitter. 85

34. In a selecting system for printing telegraphs, the combination of a normally closed line, independently operable transmitter and receiver switch mechanisms having normal conditions of rest at each of two connected stations, said transmitter switch mechanisms being operative solely under local control and independently of the line circuit to impart character signals and starting impulses to the line, each of said receiver switch mechanisms having means for initiating its operation responsive to the starting impulses imparted to the line by the distant transmitter switch mechanism, locally controlled means for continuing the 90 operation of said receiver switch mechanisms and for restoring the same to normal conditions of rest, and sets of selecting magnets adapted to be associated in order with the line and variably operated in different 100 combinations by said switch mechanisms to effect the character selections. 105

35. In selective systems for printing telegraphs in which the character signals are represented by permutations of a definite 120 number of impulses of opposite polarity, the combination of a duplexed line, independent transmitter and receiver switch mechanisms at each end of said line locally timed in operation during the character selections, each of said receiver switch mechanisms having means for controlling its operation at intervals between character selections in response to impulses imparted to the line by the distant transmitter, and sets of se- 125 130

lecting magnets adapted to be associated in order with the line and operated in different combinations by said switch mechanisms to effect the character selections.

36. In selecting systems for printing telegraphs, the combination of a normally closed duplexed line having current normally maintained thereon, independent transmitter and receiver switch mechanisms at opposite ends of said line, locally timed in operation during the character selections, each of said receiver switch mechanisms having means for arresting its operation at the end of each character selection, and means for again initiating its operation in response to starting impulses imparted to the line by the distant transmitter switch mechanism, and sets of selecting devices adapted to be associated in order with said line and variably operated in different combinations by said switch mechanisms.

37. In selective systems for printing telegraphs, a receiver having a set of selecting magnets adapted to be operated in different combinations to effect the character selections, a line relay, switch mechanism locally timed in operation during each character selection, for successively bringing said

selecting magnets into operative relation with the line, a starting magnet responsive to line impulses for initiating the operation of said receiver switch mechanism at the beginning of each signal, a locking circuit for said starting and selecting magnets, and means for releasing said locking circuit at the end of each signal.

38. In selecting devices for printing telegraphs, the combination of a transmitter for imparting the character signal to the line, a receiver having a set of selecting devices adapted to be operated in different combinations to effect the character selections, means responsive to the first impulse of each signal for initiating the operation of said receiver, means for maintaining said starting means in operated condition to continue the operation of said receiver in timed relation with said transmitter independently of the line, and means for restoring said receiver and said starting means to normal at the end of each signal.
